GOBLET OR SIMILAR ARTICLE

Frank J. Benes, Lancaster, Ohio, assignor to Anchor Hocking Glass Corporation, Lancaster, Ohio, a corporation of Delaware

Filed June 28, 1966, Ser. No. 2,846

Term of patent 14 years

(Cl. D36—8)

FIG. 1 is a side elevational view of a goblet or similar article showing my new design in the size of a water goblet;

FIG. 2 is a side elevational view of a goblet or similar article showing another form of my new design in the size of a cocktail goblet; and

FIG. 3 is a top view of the goblet shown in FIG. 1.
I claim:

The ornamental design for a goblet or similar article, substantially as shown and described.
